(57) **CLAIM**

The ornamental design for an electric pepper and sea salt grinder, as shown and described.

DESCRIPTION

FIG. 1 is a perspective view of an electric pepper and sea salt grinder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is another perspective view shown in a separated condition thereof;

FIG. 7 is a top plan view thereof;

FIG. 8 is a bottom plan view thereof;

FIG. 9 is an enlarged partial view thereof, taken from FIG. 2; and,

FIG. 10 is an enlarged partial view thereof, taken from FIG. 5.

1 Claim, 10 Drawing Sheets
